UNITED STATES PATENT OFFICE.

EDWIN M. GOLDSMITH, OF PHILADELPHIA, PENNSYLVANIA.

LEAD OR OTHER PENCIL.

SPECIFICATION forming part of Letters Patent No. 659,026, dated October 2, 1900.

Application filed October 13, 1899. Serial No. 733,459. (No model.)

To all whom it may concern:

Be it known that I, EDWIN M. GOLDSMITH, a citizen of the United States, residing in the city and county of Philadelphia, State of Pennsylvania, have invented a new and useful Improvement in Lead or other Pencils, which improvement is fully set forth in the following specification and accompanying drawings.

- 10 My invention consists of a lead or other pencil formed of a telescopic or collapsible barrel and means for connecting a length or piece of lead or marking material therewith, whereby as said lead or material is worn away 15 it may be exposed to present a fresh portion by the reduction in the length of the barrel, said piece having one end movably guided in the tip of the pencil and its other end rigidly held in the opposite end of the barrel, where- 20 by it cannot be detached through said tip.

- Figure 1 represents a side elevation of a pencil embodying my invention. Fig. 2 represents a longitudinal section thereof. Fig. 3 represents a longitudinal section thereof on 25 an enlarged scale. Fig. 4 represents a longitudinal section of a portion, showing the pencil in partly-folded condition. Fig. 5 represents a side elevation of the pencil in folded condition. Fig. 6 represents a side elevation 30 of another form of the invention. Fig. 7 represents a section of a portion of a modification.

Similar letters of reference indicate corresponding parts in the figures.

- 35 Referring to the drawings, A designates a barrel, at the forward end of which is secured the split or divided sleeve B, through which one end of the piece or length of lead or marking material C protrudes, it being noticed 40 that said barrel is formed of sections D D' of different diameters fitted to each other telescopically, so as to form a continuous length, as in Fig. 1, or be folded or partly folded, as in Figs. 4 and 5, said sections being provided 45 with shoulders E, which are adapted to abut for preventing improper separation of the sections in the direction of the arrow, Fig. 2. The end of the piece C opposite to the sleeve B is held by the head F, which is tightly se- 50 cured within the section D of the greatest

diameter of the barrel, said piece C being primarily of the length of the barrel when its sections are in extended condition and partly projecting through the sleeve B, as clearly shown in Figs. 1 and 2, it being seen that the 55 pencil may now be used as usual, the piece of lead or material C being prevented from being pushed back, owing to the head F, assisted, if desired, by the end cap G, against which the piece C abuts, as illustrated in Figs. 60 2 and 3. It will now be seen that as the lead or marking material wears away at the pencil-point the sections D D' are partly folded, thus shortening the barrel, and consequently exposing the piece C, so that more of the point 65 portion of said piece protrudes through the sleeve B. As the piece further wears away the sections are folded to a greater extent and the barrel further shortened, so as to continue the exposure of the point portion, 70 and thus the operation continues until the barrel is shortened to full extent, the several sections thereof folding one on the other, as shown in Fig. 5.

In Fig. 6 the barrel is formed of a coil H, 75 of metal or other material, the convolutions of which may fold one into the other. The piece C is secured at its inner end to a socket on the cap J; but its operation is similar to that shown in the other figures. 80

The head F may be secured to the cap G or form an integral portion, as in Fig. 7, or be secured to the interior of the section D of the barrel, as in Figs. 2 and 3.

Having thus described my invention, what 85 I claim as new, and desire to secure by Letters Patent, is—

A collapsible barrel formed of telescopic sections, a tip at one end thereof, a head in the other end rigidly secured to the section 90 thereof, and a piece of marking material in said barrel, the same being movable at one end through the said tip and guided therein and rigidly secured at the other end in said head.

EDWIN M. GOLDSMITH.
